SHIPPING CONTAINER AND PUMP THEREFOR

Filed May 20, 1931

UNITED STATES PATENT OFFICE

ANDREW A. KRAMER, OF KANSAS CITY, MISSOURI

SHIPPING CONTAINER AND PUMP THEREFOR

Application filed May 20, 1931. Serial No. 538,799.

My invention relates to shipping containers and pumps therefor, and more particularly to a liquid shipping container, such as a barrel or drum for oil or similar material, and 5 self contained means for pumping the oil or other liquid from the container.

When oil or similar liquid is shipped in a shipping container to a purchaser, the oil or other liquid is either withdrawn from the 10 container by the purchaser by means of a faucet to which the liquid is fed by gravity, or by means of a pump. With the present methods of handling oil or other liquids in drums, steel barrels or similar shipping containers, many difficulties are experienced. 15 In order that a faucet may be used on the container, it is necessary that the container be placed either permanently in a horizontal position with the faucet downward, or else placed in some sort of a tiltable frame for moving the container to a horizontal position. In either case much handling of the drum, which is quite heavy, is necessary, and if a 20 tiltable support for the drum, barrel or other container is provided it takes up a large amount of room.

Furthermore, if the liquid is dispensed from the container by means of a faucet by the action of gravity, there is much chance for 25 considerable wastage due to leaky faucets or improper closing of the same. Where a pump is used for removing the liquid from the container, it is either necessary for the purchaser of the liquid in the container to 30 supply a pump for this purpose, or that the seller furnish a pump for use in removing the liquid from the container. Ordinarily considerable difficulty is experienced by the purchaser in obtaining suitable pumps for this 35 purpose, and most of such pumps are expensive.

It is a purpose of my invention to provide a pump combined with a container in such a manner that all the difficulties experienced in 40 connection with the use of a pump and the shipping of a pump with a container, are eliminated, and furthermore, one which will be always with the container no matter how much the container may be transported from 45 place to place. This is accomplished by pro-

viding a pump that is mounted detachably within the container, and which is housed entirely within the same so that the container may be shipped in the usual manner, and when the closure member is in place theron 55 the same will be in its usual condition for shipment with the pump confined or concealed entirely within the package thus formed.

Preferably, my improved pump and the 60 mounting therefor is associated with the usual threaded filling opening for the container in such a manner that the same can be detached from the container and the container filled through the opening, after 65 which the pump is screwed in place and the closure member is screwed into the opening remaining in the container to completely close and seal the same so as to prevent escape 70 of liquid therefrom, with the pumping means entirely enclosed within the container.

It is another purpose of my invention to provide a pump mounted in the manner set forth above, which is provided with a flexible 75 discharge conduit which extends through the opening in the container to the exterior thereof, and to provide in conjunction with the mounting of the pump in the container, means for supporting the flexible conduit 80 within the container when disengaged from the pump.

It is another purpose of my invention to provide a mounting for a pump comprising a chamber located within the container with which the pump is associated, which has 85 drainage means provided therein for returning any liquid that might enter the chamber during the pumping operation, or otherwise, to the chamber formed by the container itself. While it is preferred that the closure 90 member for the opening in the container be utilized as a handle for the pump, it may be desirable to provide a separate handle for the pump, which may be more readily 95 grasped by the operator, and one form of my invention contemplates means for supporting such a handle within the container when the pump is in knocked-down condition for purposes of transporting the same from 100 place to place within the container.

Other objects and advantages of my invention will appear as the description of the drawing proceeds. I desire to have it understood, however, that I do not intend to limit myself to the exact details shown or described, except as defined by the claims.

In the drawing:

Fig. 1 is a view of a steel barrel, partly in elevation and partly in section, the same being partly broken away, showing my improved pump in position therein ready for shipment with the container.

Fig. 2 is a vertical sectional view through the pump, partly broken away, showing the same set up for pumping.

Fig. 3 is a perspective view of the bushing or tubular supporting member for the pump.

Fig. 4 is a fragmentary section of the outer end portion of the pump and the adjoining portion of the container, showing a modified construction.

Fig. 5 is a perspective view of the handle that may be provided for the pump shown in Fig. 4.

Fig. 6 is a fragmentary view similar to Fig. 4 of another modification, showing the pump in operating condition.

Fig. 7 is a view similar to Fig. 6 of said modification, showing the pump in shipping condition.

Fig. 8 is a perspective view taken on a slight modification.

Fig. 9 is a fragmentary section showing a further modification.

Referring in detail to the drawing, in Fig. 1, my invention is shown as being applied to a shipping container 10, which is shown as being in the form of a steel barrel or drum, having a head 11, and having a collar 12 mounted in an opening 13 in the head 11, said collar 12 being secured to the head 11 of the container in any suitable manner, as by means of welding, and having internal threads 14 thereon.

Ordinarily a screw-threaded plug engages with the threads 14 on the collar 12, the container being secured to said collar. In accordance with my invention, as shown in Figs. 1 to 4 inclusive, I apply my improved pump through the opening provided in the collar 12, and secure the same detachably to said collar so that the entire pump can be removed from the barrel so as not to interfere with the filling of the barrel through the opening provided in said collar. The mounting for my improved pump comprises a fitting made in the form of a tubular member, having both an internally and externally threaded end portion 15 of maximum diameter, and a tapering portion 16 extending to a transverse wall portion 17, from which the downwardly directed substantially annular flange portion 18 extends, said flange portion receiving the tubular pump barrel or cylinder 19 therein, the pump cylinder being se-

cured to the flange 18 in any desired manner.

It will be seen that, as the pump cylinder 19 and all portions of the fitting carrying the same inwardly from the threaded end 15 thereof are of smaller diameter than the threaded end 15, and do not extend laterally beyond the external threads on the portion 15, the entire pump can be passed through the screw-threaded opening 14 in the collar 12 until the threaded end 15 engages therewith, whereupon the pump can be rotated to screw the portion 15 thereof into the internally threaded portion 13 of the collar 12. In order to facilitate the turning of the fitting in the threaded collar 12, a plurality of transverse grooves or notches 20 are provided in the outer face thereof, with which a tool or pointed member may be engaged to turn the pump mounting fitting.

Mounted within the pump cylinder or barrel 19 at the lower end thereof, is a valve 21, which is movable on the valve stem 22 having the head 23, and which seats over the openings 24 in the flanged closure member 25 at the bottom or inlet end of the pump. The usual plunger or piston 26, having the flexible member 27 associated therewith to seal the space between the piston and the wall of the cylinder 19, is mounted in the usual manner on a piston or pump rod 28, which extends slidably through an opening 29 in the transverse wall 17.

In the arrangement shown in Fig. 2, the outer end of the pump rod 28 is threaded at 30, and is received within the screw-threaded opening 31 in the plug 32, the plug 32 being provided with a gasket 33, as is customary, underlying the flange 34 thereon and having an externally threaded portion 35 that engages with the internal threads on the end portion 15 of the pump supporting fitting. The plug is otherwise made in the usual external form for engagement of a wrench therewith, both on the outside thereof and in the socket 36 provided in said plug.

The transverse wall 17, which also serves as a head for the pump cylinder or barrel at the discharge end of the pump, is provided with an internally threaded opening 37, with which the externally threaded coupling 38 on the flexible metallic conduit 39 engages, said flexible metallic conduit 39 comprising the discharge pipe or conduit for the pump. A plurality of drain openings 40 are provided in the side wall of the fitting closely adjacent the transverse wall 17, to permit any liquid that might accumulate in the chamber 41 formed within the fitting, to run back into the container proper.

The pump, in condition for pumping the liquid, is shown in Fig. 2. In Fig. 1 the pump is shown in the knocked-down condition in which the same is shipped inside the container. When the container has been

filled with liquid, the pump not being in position while the filling operation is taking place, the pump is inserted through the opening in the collar 12, and the threaded end 15 5 on the pump supporting fitting is screwed into position in the collar so that the outer end thereof is either flush with or slightly below the outer rim or edge portion of the collar.

10 The discharge conduit is detached from the pump and is inserted with the flexible portion 39 thereof, downwardly through the opening 37, the conduit 39 being of smaller diameter than the opening 37 to permit the 15 passage thereof through said opening into the pump cylinder or barrel 19 where the same will remain during shipment of the container. This is possible due to the fact that the threaded coupling 38 has a larger diameter 20 than the conduit 37, being in that respect, both a bushing and a coupling. After this has been done the pump rod is moved downwardly by means of the plug member 32 until the external threads on the plug member 25 engage with the internal threads on the portion 15 of the pump supporting fitting, whereupon the plug is rotated in the usual manner to tighten the same down on the fill collar 12, the flange 34 thereof overlapping the collar 30 sufficiently to provide a tight joint at the opening in the container when the plug is screwed down tightly. The plug will then serve as a closure for the chamber 41, preventing the disengagement of the conduit 35 member 39 from its position extending through the opening in the transverse wall 17, and preventing any appreciable endwise movement thereof.

For the sake of simplicity, it is advisable 40 to use the closure member 32 as a handle for the pump. It is, of course, not as readily grasped as a relatively narrow elongated handle member, and it may be found desirable to provide such a handle member which 45 will also be housed within the container when the package, including the pump confined within the container is ready for shipment.

A slightly modified form of the invention is shown in Figs. 4 and 5, in which such a 50 handle member is provided. The plug member 32 is the same as previously described, as is also the fill collar 12. The fitting for supporting the pump is also made substantially the same, except for the provision of an additional threaded opening therein, and the 55 same numerals are accordingly applied to the parts that correspond in Fig. 4 to the parts previously described in connection with Figs. 1 to 3 inclusive. The pumping mechanism, 60 including the pump barrel and pump rod are also the same as previously described. Instead of providing merely the internally threaded opening 37 in the transverse wall portion 17 of the pump supporting fitting, a 65 second internally threaded opening 37' is

provided therein, and the handle member 42, which is made of a flat strip of metal, and which has the right angular end portion 43 and the internally threaded opening 44, is adapted to be passed through the opening 37' with the angular end 43 resting on the top surface of the transverse wall 17, and the body portion depending into the pump barrel 19.

In this form of the invention, the plug 32 is removed from the threaded end 30 of the rod 28, and the handle 42 is threaded thereon when the pump is got ready for use to pump the contents out of the barrel or other container. A flexible conduit 39 may be connected with both the openings 37 and 37' when pumping is commenced, thus increasing the capacity of the pump should this be desired, or if only one flexible discharge conduit is to be used, as in the previously described form, a threaded plug 45 is provided, which is used to close the opening 37' while pumping is going on, the plug being carried within the chamber 41 when the device is in knocked-down condition for shipping purposes, as 90 will be evident from Fig. 4.

Instead of carrying the handle as shown in Fig. 4, a handle 42', such as shown in Fig. 9, may be provided having the threaded opening 44, but having no angular end, but 95 being provided with any suitable means, such as the opening 47 for receiving a tie wire 48 for securing the handle to the flexible spout or discharge conduit 39 on the lower end thereof suspended within the pump cylinder 100 19 when ready for shipment.

It is desirable that the pump be made of such length that it would extend to the head 11' of the container opposite the head 11, which may be referred to as the bottom thereof, but in order that the same will not engage the bottom so as to prevent the pump from operating to withdraw the liquid from the container, a pair of projecting legs or lips 46 are provided on the pump barrel, which engage the wall 11' so as to space the lower end of the barrel from said wall so that liquid may enter the inlet end of the pump.

In Figs. 6 and 7, a further modification is shown for application to a shipping container having a different kind of fill collar. The form of container shown is similar in structure to that previously described, but instead of having an internally threaded collar thereon, the container is provided with an upstanding threaded collar 49 secured to the outwardly directed flange 50 on the head 11 of the container, the collar being made of sheet metal and having threads formed thereon and being provided with an inturned peripheral flange 51.

In this form of the invention the pump barrel 19' is just like the pump barrel 19 previously described, except for a slight lat- 130

eral flare 52 at the top end thereof, and the pumping mechanism within the same, is the same as previously described. The bushing or pump supporting fitting is the same as shown in Figs. 1 to 3 inclusive, except for a lateral enlargement in the same at one point therein corresponding to the lateral flare 52 in the pump, and the provision of different means for securing the same to the fill collar. The wall 17 is slightly enlarged laterally at 53 to provide room for the opening 37 therein, and the tubular wall 18 is correspondingly offset slightly laterally at 54, it being obvious that this arrangement can be used whenever it is found necessary to do so, to provide sufficient material adjacent the opening 37. The tubular conduit 39 is associated with the bushing or fitting in the same way as previously described, both in shipping and operative position.

The outer end of the bushing is not threaded, however, but is provided with a lateral circumferential flange 55 which overlies the flange 51, a gasket 56 being provided between said flanges. The fitting or bushing is provided with openings in the portion thereof in such a position that the screws 57 threaded therethrough will engage under the flange 51 to secure the same on the fill collar. A handle 58 is secured onto the threaded end 30 of the pump rod 28 and is shipped within the chamber 41, as shown in Fig. 7. A closure or cap 59 having threads 60 formed on the depending flange thereon cooperates with the collar 49 and has a gasket 61 provided on the inner face thereof, and serves to clamp said gasket against the flange 55 and the gasket 56 between the flanges 51 and 55 when screwed down tight.

Instead of providing the grooves or notches 20 for turning the threaded bushing, a plurality of ribs 62 may be provided projecting into the chamber 41, as shown in Fig. 8, for engagement by a tool to turn the bushing.

What I claim is:—

1. The combination with a container having an opening therein, of a collar mounted in said opening, a pump carried by said collar comprising a threaded tubular portion mounted within said collar and a plug having sealing engagement with said collar and screw-threadedly engaging said threaded tubular portion.

2. The combination with a shipping container having a discharge opening therein, of a pump mounted in said container, means for mounting said pump within said container comprising a member having a fluid tight connection with said container at said opening and comprising a plug receiving portion mounted in said opening and a plug interlockingly engaging said plug receiving portion to close said container, and confine

said pump entirely within the normal outlines of said closed container.

3. The combination with a shipping container having an opening therein, of means at said opening for mounting a pump in said container to project inwardly from said opening, said pump having operating means adapted to extend through said opening to the exterior of said container, closure receiving means on said container at said opening and a closure interlocking with said closure receiving means to provide a liquid tight joint therebetween, said closure confining said pump and operating means within said container while in interlocking engagement with said closure receiving means.

4. The combination with a liquid container having a discharge opening therein, of a liquid tight closure for said opening and a pump in said container comprising a member extending only inwardly beyond said closure and supporting a flexible discharge conduit for said pump within said liquid container when not in use.

5. The combination with a liquid shipping container having an opening therein, of a pump mounted entirely within said container and carried thereby at said opening and a closure for said opening adapted to close said container liquid tight with said pump concealed within said container by means of said closure, said closure holding said pump against removal from said container.

6. The combination with a liquid shipping container having an opening therein, of a pump detachably mounted entirely within said container and carried thereby at said opening and a plug for said opening adapted to close said container liquid tight with said pump concealed within said container by means of said plug, said plug holding said pump against removal from said container.

7. The combination with a liquid shipping container, of pumping mechanism mounted within said container, said container having an opening therein whereby access may be had to said pumping mechanism, said pumping mechanism being detachably connected with said container at said opening and a closure for said opening completely enclosing said pumping mechanism within said container, said closure holding said pumping mechanism against removal from said container.

8. A liquid shipping package comprising a liquid container and pumping mechanism detachably mounted in and opening in and completely confined within said container, and means engaging said container, to hold said pumping mechanism against removal from said container.

9. A liquid shipping package comprising a liquid container and pumping mechanism detachably mounted in and completely con-

fined within said container, and means providing a detachable liquid tight closure for said container at said pump mounting, said means holding said pumping mechanism against removal from said container.

10. In a shipping container having an opening therein, a threaded collar mounted on said container at said opening, a tubular member screw-threadedly engaging said collar and extending into said container, said tubular member having a transverse wall spaced from the wall of said container, and a pump in said container having a flexible discharge conduit provided with an enlarged end, said transverse wall having an opening therein larger than said conduit except at said enlarged end through which said conduit is adapted to be suspended while detached from said pump.

11. In a shipping container having an opening therein, a threaded collar mounted on said container at said opening, a tubular member screw-threadedly engaging said collar and extending into said container, said tubular member having a transverse wall spaced from the wall of said container, a pump in said container and a pump handle, said transverse wall having a pump rod opening and a second opening therein through which said pump handle is adapted to be suspended while detached from said pump.

12. In a shipping container having an opening therein, a threaded collar mounted on said container at said opening, a tubular member screw-threadedly engaging said collar and extending into said container, said tubular member having a transverse wall spaced from the wall of said container and comprising the head of a pump, a pump barrel extending inwardly from said wall, said wall having an opening therein, a pump rod extending through said opening in said wall, said wall having a threaded opening therein and a flexible discharge conduit having an enlarged threaded member engaging in said threaded opening, said conduit being adapted to be passed through said threaded opening and suspended in said pump barrel from said wall by means of the enlarged member thereon.

13. In a shipping container having an opening therein having threaded means thereon at said opening, a tubular member open at the outer end thereof and detachably engaging said threaded means and extending into said container, a pump provided on the inner end of said tubular member and lying entirely within said container and a closure for the opening in said shipping container and said tubular member, said closure holding said pump against removal from said container.

14. In a shipping container having an opening therein having threaded means thereon at said opening, a tubular member

open at the outer end thereof and detachably engaging said threaded means at its outer end and extending into said container, a pump provided on the inner end of said tubular member and lying entirely within said container having a detachable flexible discharge conduit extending through said opening in said container to the exterior thereof, and a closure for the opening in said tubular member.

15. In a shipping container having an opening therein having threaded means thereon at said opening, a tubular member open at the outer end thereof and detachably engaging said threaded means at its outer end and extending into said container, a pump provided on the inner end of said tubular member and lying entirely within said container, said tubular member having a transverse wall spaced from the wall of said container and forming the head of said pump and being internally threaded at its outer end, a pump rod extending through said transverse wall, and a threaded closure for the opening in said tubular member mounted on said pump rod and engaging the internal threads on said tubular member.

16. In a shipping container having an opening therein, a threaded collar mounted on said container at said opening, a tubular member screw-threadedly engaging said collar and extending into said container, said tubular member having a transverse wall spaced from the wall of said container, and a pump in said container having a pump rod extending through an opening in said transverse wall, said transverse wall providing a chamber within said tubular member, said chamber having drainage openings therein leading into the container outside said pump.

17. In a shipping container having an opening therein having closure receiving means thereon at said opening, a closure engaging said means to seal said container against leakage, a tubular member having its outer open end detachably connected with said means and extending into said container, a pump provided on the inner end of said tubular member and lying entirely within said container, said tubular member having a transverse wall spaced from the ends thereof forming the head of said pump, and providing a chamber within said container, and a pump rod extending through said transverse wall, said closure closing the outer open end of said tubular member.

18. In a shipping container having an opening therein having closure receiving means thereon at said opening, a tubular member having an outer open end detachably connected with said means and having a reduced inner end extending into said container, a pump provided on the inner end of said tubular member and lying entirely

within said container, a transverse wall in said tubular member spaced from the ends thereof forming the head of said pump and having a discharge opening therein, and a 5 detachable flexible spout extending from said opening in said wall outwardly through said closure receiving means.

19. In a shipping container having an 10 opening therein having closure receiving means thereon at said opening, a tubular member having its outer open end detachably connected with said means and having a reduced inner end extending into said container, a pump provided on the inner end 15 of said tubular member and lying entirely within said container, and a closure engaging said closure receiving means to hold said pump in inoperative position and against removal from said container.

20. The combination with a container having an opening therein, of an externally threaded collar provided on said container at said opening, a pump carried by said collar comprising a flanged tubular portion extending through said collar with said flange engaging said collar and a cap having threaded engagement with said collar and sealing engagement with the flange on said tubular portion of said pump, said cap enclosing said pump to prevent access thereto when said cap is in container closing position.

21. The combination with a shipping container having a discharge opening therein, 35 of a pump mounted in said container, means for mounting said pump within said container comprising a member having a fluid tight connection with said container at said opening and comprising a cap receiving portion mounted at said opening, and a cap interlockingly engaging said cap receiving portion to close said container and confine said pump entirely within the normal outer lines of said closed container.

45. 22. The combination with a liquid container having an opening therein, of a pump detachably mounted within said container and carried thereby at said opening, a cap receiving member on said container at said opening, 50 and a cap engaging said cap receiving member to close said container liquid tight in cooperation with said pump, said cap concealing said pump within said container and holding said pump against removal from said container.

23. The combination with a container having an opening therein, of an externally threaded annular member on said container 60 surrounding said opening, a pump secured to said annular member and extending into said container, said pump comprising a tubular portion open at one end thereof mounted within said annular member and forming an outwardly opening chamber therein, a cap having threaded engagement with said an-

nular member to close said opening, said cap closing said chamber and confining said pump in inoperative position when in container closing position, and means cooperating with said cap to provide a liquid tight seal at said 70 opening.

24. The combination with a container having an opening therein, of an externally threaded annular member on said container surrounding said opening, a pump secured to said annular member and extending into said container, said pump comprising a tubular portion open at one end thereof mounted within said annular member and forming an outwardly opening chamber therein, a cap having threaded engagement with said annular member to close said opening, said cap closing said chamber and confining said pump in inoperative position when in container closing position, a pump handle confined in said chamber by said cap, and means cooperating with said cap to provide a liquid tight seal at said opening.

25. In a container having an opening therein, a collar mounted on said container at said opening, a tubular member engaging said collar and extending into said container, said tubular member having a transverse wall spaced from the outer end thereof and comprising the head of a pump, a pump barrel 95 extending inwardly from said wall, said wall having an opening therein, a pump rod extending through said opening in said wall, said wall having a threaded opening therein and a flexible discharge conduit having an 100 enlarged threaded member engaging in said threaded opening, said conduit being adapted to be passed through said threaded opening and suspended in said pump barrel from said wall by means of the enlarged member thereon.

In testimony whereof, I hereunto subscribe my name this 13th day of May, 1931.
